ADJUSTABLE COLLAR

Helen Thomson Thomas, Montclair, N. J.

Application October 29, 1952, Serial No. 317,405

12 Claims. (Cl. 2-133)

1

My invention relates to a decorative collar lending itself particularly to the ornamentation of ladies' wear.

It is an object of the invention to provide an improved device of the character indicated.

It is another object to provide a decorative ladies' collar lending itself, without structural change, to a wide variety of ornamental effects.

Other objects and various further features of novelty and invention will become apparent or will occur to those skilled in the art from a reading of the following specification in conjunction with the accompanying drawings. In said drawings, which show, for illustrative purposes only, preferred forms of the invention:

Fig. 1 is a plan view of a collar incorporating features of the invention, and shown flattened, as when ironed, ready for use;

Fig. 1a is an enlarged fragmentary sectional view in the plane 1a-1a of Fig. 1;

Figs. 2 to 5 are plan views similar to Fig. 1 and illustrating alternative collar construction; and

Figs. 6 to 15 are front-elevation views illustrating a number of suggested alternative employments of collars of the types shown in Figs. 1 to 5.

Briefly stated, my invention contemplates a novel collar construction lending itself to a wide variety of applications, without requiring structural change in the collar itself. The collar may be said to comprise an elongated neck band of substantially uniform width and extending, in one integral piece (which may be two pieces hemmed and stitched together), from one end portion running substantially with one weave direction (e. g. lengthwise) of the material, through a central bias-cut portion, and to another end portion running substantially with the other weave direction (e. g. crosswise) of the material. The overall planform of the collar may be substantially arcuate, extending through substantially 90 degrees; and the arc may be a continuously circular arc, or a composite of a plurality of straight or large-curvature sections joined to each other. The ends of the collar may be integrally formed with transverse tabs projecting predominantly in one direction only, as toward the center of the effective overall arc upon which the collar is constructed; these projections may be rounded projections, squared, triangular, or otherwise, to produce particular decorative effects.

Referring to Fig. 1 of the drawings, my invention is shown in application to a collar comprising an elongated neck band 21 of substantially

2

uniform width and extending between end portions 22-23 cut substantially on the two weaves of the material, as suggested by the shading, and integrally joined to a center section 24 cut on the bias. The overall effective shape of the neck band 21 may be generally arcuate, and in the form shown the collar 21 is cut from a strictly circular arc running through substantially 90 degrees and thereby defining between relatively wide central limits an elongated center section 24, on the bias of the material. The effective overall length of the bias section, as over the 45-degree span identified by locations 24', may be said to be preferably of the order of seven to nine tenths of the neck-band measurement of the wearer.

In accordance with a feature of the invention, the end portions 22-23 are integrally formed with transverse projections or tabs 25-26; that is, projections 25-26 extend transversely of the end portions 22-23 and prominently in one direction, as in the radially-inward direction shown. For appearance's sake, I prefer that the projections 25-26 be smoothly joined to the end portions 22-23, as by a curve 27 of radius substantially equal to the width of the neck band 21. Also, I prefer that the projections 25-26 be of length and width substantially equal to the width of the neck band 21, although it will be understood that other decorative styles and effects may be achieved with other proportions for the tab projections 25-26.

In order that my collar may lend itself to as wide a variety of applications as possible, I prefer that it be made of two pieces of material 21-21', hemmed and stitched back to back, as suggested in Fig. 1a. The cuts for the two pieces 21-21' should be the same (as described above) and different ornamental effects may be achieved by using the same material, or similar materials of different color, for the respective pieces 21-21', as will be understood.

Figs. 2 and 3 illustrate alternative neck-band plan-forms for my arcuate collar. In Fig. 2, the neck band 30 consists essentially of a succession of integrally-joined, relatively straight sections 31-32-33, inclined to one another so as to present an overall arcuate appearance, again of arcuate extent approximating 90 degrees. Thus, the end portions 31-33 may be substantially at right angles to each other so that when the center section 32 is cut on the bias, as suggested by the shading, the end portions 31-33 may be aligned with the respective weave directions of the material. The straight sections 31-32-33

3

may be joined directly to each other to provide well-defined corner intersections, but I prefer smoothly rounded corners between these straight sections, as shown. Again, rounded projections 25-26 may be integrally formed at the ends of the end portions 31-33.

In Fig. 3, the neck band 35 is formed of a continuous succession of relatively curved sections 36-37-38, again smoothly joined and presenting an overall arcuate appearance, preferably of an extent approximating 90 degrees. The curved sections 36-37-38 may be of larger radius than the overall effective arc of the neck band 35 as shown, and the end portions are preferably integrally formed with projecting tabs 25-26 as described above for the other forms.

The end tabs or projections 25-26 have thus far been shown as of fattened, rounded, generally trapezoidal or triangular shape, but it will be understood that other configurations may be adopted for particular decorative effects. For example, in Fig. 4, I illustrate the formation of a square or rectangular projecting tab 39 at the end of the end portion 40 of an arcuate collar, which may have a neckband pattern conforming with any of the forms shown in Figs. 1-3. The length and width of the projection 39 are preferably substantially equal to the width of the neck band 40 and, if desired, slightly rounded corners 41-42-43 may mitigate the frigid appearance of a contour geometry that is too strictly square or rectangular. In Fig. 4a, the neck band 45 is provided with generally triangular projecting tabs, as at 46, and again the overall width and length of tabs 46 may be substantially the effective width of the neck band 45.

In Fig. 5, I illustrate the employment of projecting tabs 47-48 of generally the shape illustrated at 25-26 in Figs. 1-3, but instead of projecting inwardly of the effective arc, the projections 47-48 extend outwardly of the overall curvature of collar 49.

In Figs. 6-15 inclusive, I illustrate ten of the many possible employments of my collar with a view to suggesting something of the variety of ornamental effects achievable without in any way changing the structure of the collar. In these figures, the particular collar employed is of the variety illustrated in Figs. 1 or 3, but it will be understood that the ornamental effects achieved may be just as varied, or possibly even further varied, for the forms of Figs. 2, 4, 4a, and 5.

In Fig. 6, the collar is merely draped around the neck, with the collar ends hanging and separated, and with the projections 25-26 facing each other. When using the collar in this manner, it need only be tacked by lightly stitching to the desired basic dress, blouse, or other garment, as will be understood.

In Fig. 7, the spaced ends of the collar are brought together, with the tabs 25-26 overlapping, so as to present a trim V appearance, as when setting off a basic garment having a similar neckline.

In Fig. 8, the end portions of the collar are crossed or overlapped at 50, and the tabs 25-26 project away from the crossed-over end portions.

In Fig. 9, the tabs 25-26 are folded horizontally outwardly on a line such that, when tacked back-to-back, as at 51, the overall appearance will be a trim V, coupled with the suggestion of a simplified tie.

In Fig. 10, the end portions of the collar are folded against each other and tacked at 52, with

4

the tab projections 25-26 separately projecting below and away from the fold 52.

In Fig. 11, the respective tabs 25-26 are folded back over the end portions of the collar to which they are contiguous, and are tacked to each other so as to present the appearance of a simplified upwardly-extending bow tie on a V collar.

In Fig. 12, the end portions of the collar are loosely tied over each other and are draped downwardly, with the tabs 25-26 hanging one above the other and pointing in the same direction.

In Fig. 13, the bias cut of the central section of the collar is shown to facilitate the flaring of the central portion of the collar to produce a lapel effect, and the ends of the collar are tacked to each other with the projections 25-26 facing in opposite directions.

In Fig. 14, a more limited extent of the central or bias portion of the collar is flared, as at 54, to produce a more limited lapel effect, and the tab projections are interlocked with each other after crossing over the end portions of the collar at 55. It will be noted that flared lapel effects as illustrated in Figs. 13 and 14 may be used with a V-neck basic garment, by tacking the tabs 25-26 and other unflared portions of the collar underneath the basic garment, thus allowing only the flared material to show and to set off the V neckline.

In Fig. 15, the collar is wrapped completely around the neck in a relatively tight yoke, and the end portions extend from beneath this yoke with the projecting tabs 25-26 tacked more to the shoulder than to the front of the basic garment.

It will be seen that I have disclosed a relatively simple collar construction lending itself to a wide variety of alternative applications in order to achieve a corresponding variety of decorative effects. This construction may be useful to enable the wearer, merely by changing collar tacking on a particular garment, to wear the same garment on several occasions even throughout the same day, and yet to present the appearance of having freshly changed on each successive occasion.

While I have described the invention in detail for the preferred forms shown, it will be understood that modifications may be made within the scope of the invention as defined in the claims which follow.

I claim:

1. In a collar, a continuous band of generally arcuate planform extending through substantially 90 degrees and including, at opposite ends and thus substantially 90 degrees apart, integral tab projections extending symmetrically with respect to each other and transversely of said band and predominantly to one side of said band, the central portion of said planform being substantially on the bias, whereby the ends of said collar are substantially on the straight cut of the material, said arcuate planform being of an exaggerated length such that the ends may be tied or otherwise ornamentally combined.

2. A collar according to claim 1, in which said projections extend generally radially inwardly.

3. A collar according to claim 1, in which said projections extend generally radially outwardly.

4. A collar according to claim 1, in which said band is a substantially continuous circular arc.

5. A collar according to claim 1, in which said band comprises a continuous succession of inclined relatively straight sections.

6. A collar according to claim 1, in which said band is a continuous succession of relatively curved sections of radius substantially larger than the mean effective radius of said arc.

7. In a collar of the character indicated, a continuous neck band of substantially uniform width and having an effective overall curvature extending substantially through 90 degrees of a woven material, the center portion of said 90 degrees effective curvature being on the bias, whereby the end portions are in substantial alignment with the respective predominant weave directions of said material, said neck band being of an exaggerated length such that the ends may be tied or otherwise ornamenteally combined in a plurality of readily convertible relationships.

8. In a collar, an elongated neck band of substantially uniform width and including a center section on the bias of the collar material and of sufficient effective extent to envelope substantially seven to nine-tenths of a neck measurement and integrally joined to end portions substantially aligned with the weave of material of said neck band, said center section being the only portion on the bias, whereby said end portions may not substantially stretch but form-fitting may be confined essentially to said center portion, said neck band being of an exaggerated length such that the ends may be convertibly combined in a plurality of ornamental relationships.

9. In a collar of the character indicated, an elongated generally arcuate neck band of substantially uniform width, and including at opposite ends elongated portions substantially aligned with the weave of the material of said neck band and integrally joined to a center por-

tion substantially on the bias of said material, said center portion being the only portion on the bias, and integral transverse projections projecting transversely and predominantly in one direction substantially to exclusion of the other direction, said projections being substantially at the ends of both said end portions, said neck band being of an exaggerated length such that the ends may be convertibly combined in a plurality of ornamental relationships.

10. A collar according to claim 9, in which each of said projections is of a width substantially equal to that of said neck band.

11. A collar according to claim 9, in which each of said projections extends transversely as aforesaid by an amount substantially equal to said uniform width of said neck band.

12. A collar according to claim 9, in which each of said projections is joined to an end portion by an outer rounded curve of radius substantially equal to the width of said neck band.
